MULTIPLE FUSE

Samuel Joseph Wynn, Norwalk, Conn.

Application July 21, 1933, Serial No. 681,401

14 Claims. (Cl. 200—125)

This invention relates to new and useful improvements in a multiple fuse.

It is an object of this invention to construct a multiple fuse which is characterized by the ability to open a circuit of high amperage without damage to the fuse body, emission of flame, and without blowing any of the links except the link in circuit. In order for a fuse to pass the Underwriters Laboratories short circuit test, it is necessary among other things that it be capable of opening a circuit having a current magnitude of approximately 10,000 amperes. The arc resulting from opening a circuit of this type tends to blow all of the links simultaneously instead of the one in circuit only and also tends to disrupt the body of the fuse, or emit flame which constitutes fire hazard.

The invention has for a still further object the construction of a multiple fuse which is characterized by a fume chamber for selective engagement over the portion of each fuse link which blows to open the circuit, and connected by unrestricted small passages with a second fume chamber having fume escape passages restricted to bleed off with relation to said unrestricted passages. This arrangement is an exceptionally important feature of the invention in that the fumes and flames build up a back pressure within the chambers which cause the extinguishing of the flame.

As a further object of this invention it is proposed to construct a multiple fuse in which there is a core rotatively mounted and formed with an interior fume chamber having the entrance port selectively engageable over fuse elements mounted within the fuse body, and in which the core has a peripheral groove fume chamber connected by openings to the interior fume chamber in a manner so as to encase and choke the flame and gases formed by the blowing of one fuse, and further to allow the gradual escape of the fumes through a tortuous path.

As a still further object of this invention it is proposed to arrange a cap over said peripheral groove fume chamber and over a portion of the body of the fuse in a manner so as to allow the gradual escape or bleed off of the fumes as well as provide a secondary fume chamber wherein back pressure may build up and tend to extinguish the arc as stated in the previous paragraph.

Furthermore as another object of this invention it is proposed to arrange a fire resistant transparent or translucent material within the cap and beneath a portion provided with apertures denoting selectively each of the fuse ele-

ments, and to provide an arrangement to discolor the fire resist material selectively beneath each of the apertures as the particular fuse element denoted by said aperture is blown. With this arrangement the inspection of the fuse is sufficient to inform the number of good fuse elements and those blown.

Furthermore the invention also proposes the arrangement of the body and the core of the fuse in a manner so as to have a plurality of 10 interengaging shoulders with the fuse elements engaged therebetween and following the contour between the body and core and set within grooves in one of these parts in a manner so as to form a tortuous passage for the flames and fumes and so force the flames and fumes into the interior fume chamber of the core.

Furthermore the invention contemplates the forming of the core of two sections connected for unitary rotation by the provision of a finger 20 on one of the sections engaging into an opening in the other of the sections, and for the purpose of convenience in molding the core and furthermore for the provision of a construction in which one of the core sections completely covers the 25 end contact of the multiple fuse.

Furthermore it is proposed to arrange the opening in which the finger mentioned in the previous paragraph extends in such a manner that the opening is of greater size than the finger 30 and forms the entrance to the fume chamber within the interior of the core.

To increase the effective operation of the fuse the invention also proposes an arrangement whereby each of the fuse elements has a reduced 35 portion located in the vicinity of one of the shoulders between the body and the core and so arranged, that when the member fuse element is blown it will be blown at the reduced portion and so direct the flame and fumes through the entrance port of the core into the interior fume chamber.

Furthermore the invention contemplates arranging each of the fuse elements in a manner 45 so that the top ends are horizontal and disposed upon a horizontal shoulder between the core and the fuse body, and particularly within cavities formed in said horizontal shoulder.

As a further object of this invention it is proposed to arrange a horizontal contact spring 50 adapted to selectively engage within the cavities mentioned in the previous paragraph and connected with a ring in sliding contact to an extension of the shell contact thus concluding the 55

circuit from the central contact of the multiple fuse to the shell contact.

The invention still further proposes an arrangement whereby the lock construction is provided for holding the core against rotation and necessitating the use of a key for turning the core to reset its position.

A still further object of this invention is the construction of a multiple fuse as mentioned which is simple and durable and that may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

20 Fig. 1 is a plan view of a multiple fuse constructed according to this invention.

Fig. 2 is an enlarged sectional view taken on the line 2—2 of Fig. 1.

25 Fig. 3 is a horizontal sectional view taken on the line 3—3 of Fig. 2.

Fig. 4 is a fragmentary vertical detailed view taken on the line 4—4 of Fig. 2.

Fig. 5 is a fragmentary detailed view taken on the line 5—5 of Fig. 2.

30 Fig. 6 is a fragmentary horizontal sectional view taken on the line 6—6 of Fig. 2.

Fig. 7 is a fragmentary view similar to a portion of Fig. 2 but illustrating a modified arrangement.

35 The multiple fuse according to this invention comprises a fuse body 10 provided with a plurality of fuse elements 11. These fuse elements are arranged within grooves formed upon the interior face of the body, see Fig. 6. Each of 40 the fuse elements is connected at its lower end, and there connected with a central contact 12 in the form of a rivet engaged through the bottom of the fuse body. The rivet is punched at its inner end so as to securely hold its place. A 45 small washer 13 is interposed between the punched end of the rivet and the junction of the fuse elements 11 to insure proper electrical connection. The exterior of the fuse body is provided with a customary shell contact 14.

50 A core is rotative within and projects from the fuse body and is composed of an upper section 15 and a bottom section 16. This core is formed with an interior fume chamber 17, having an entrance port 18 at its bottom adapted to selectively engage over portions of the fuse elements 11.

55 The core is also provided with a second fume chamber shown specifically to comprise a peripheral groove fume chamber 19 connected with unrestricted openings 20 to the interior fume chamber 17. The unrestricted openings 20 preferably should be diametrically opposite each other and of substantially elliptical shape and slightly tapered as shown in Fig. 2 to facilitate the manufacture of the core. Since the core is a moulded part the arrangement of the openings 20 allows the core to be withdrawn from the mould after the core is moulded.

60 To facilitate the rotating of the core it is provided at the top with an oblong shaped handle 21. The interior fume chamber 17 is so formed within the core that there is a thin upper flange 22 forming the top side of the peripheral groove fume chamber.

65 The cap 23 is engaged over the peripheral fume chamber 19 and engages over a portion of

the body 10. To insure the proper holding of the cap its bottom end 24 is bent over an exterior shoulder formed upon the body of the fuse. The plurality of longitudinal grooves 25 are arranged within the periphery of a shoulder at the top of the fuse body so as to provide a tortuous passage from the peripheral fume chamber 19 to the atmosphere. In other words fumes within the chamber 19 may escape through the restricted grooves 25 to the atmosphere.

An arrangement is provided whereby there is an indication as to the number of fuses blown. This arrangement comprises a sheet of fire resistant transparent or translucent material 26 arranged in fixed relation with the cap 23 and particularly below the top of the cap. The top of the cap is formed with a number of apertures 27 numerically corresponding with the number of fuse elements and arranged spaced from each other corresponding with the spacing of each of 20 the fuse elements 11. The flange 22 is provided with a V-shaped opening 28 adapted to expose a small area of the fire resistant material 26 to the groove fume chamber 19. It will readily be understood fumes and flame from the fume 25 chamber 19 act against the small area of the fire resistant material 26 which becomes blackened or darkened and this area will be viewable through one of the openings 27. As the core is rotated to a new position the V-shaped opening 30 28 correspondingly moves and so assumes a new location beneath a different one of the openings 27 and in this manner the area beneath the openings 27 are selectively blackened as each of the fuse elements 11 are blown. The arrow 29 upon the handle 21 of the core indicates the particular position of the core in which one specific fuse element 11 indicated by the aperture 27 in line with the arrow is in circuit between the contact shell and the central contact of the fuse.

40 A plurality of shoulders 30, 31 and 32 are formed between the body of the fuse and its core. These shoulders are horizontal and are connected with each other by vertical portions or inclined portions. The fuse elements 11 are arranged in grooves in the fuse body and conform with the contour between the fuse body and the core. The plurality of shoulders form a tortuous path to prevent the fumes and flame passing up between the fuse body and the core. Thus the fumes and flame take the path of least resistance which is through the entrance port 18 into the interior fume chamber 17. Portions of each of the fuse elements 11 are reduced upon one of the shoulders or between certain of the shoulders, and as shown in Fig. 2, upon the inclined portion located between the shoulders 30 and 31. It is an object to so locate the reduced portions, one of said reduced portions is illustrated in Fig. 3 and indicated by numeral 11', that it is immediately below the entrance port 18 when the port is located over the member fuse element in the circuit. It will be readily understood that when the fuse element is blown, it is at the reduced portion 11' which is electrically 55 the high resistance point and so the resultant flame and gaseous fumes are immediately discharged within the fume chamber 17.

60 As previously stated the core of the multiple fuse is formed from the sections 15 and 16. The upper section 15 is provided with a finger 33 which extends downwards into a portion of the opening 18 and so connects the sections of the core for unitary rotation. The lower section of the core 16 serves to cover the central contact 75

12 and also to cover all of the fuse elements 11 except the one which is exposed through the entrance port 18. Similarly the upper section 15 of the core serves to cover and enclose within their grooves, each of the upper portions of the fuse elements 11.

The extreme upward ends of each of the fuse elements 11 are disposed horizontally and extend across the bottom of cavities 34 formed in the 10 upper shoulder 32 in the fuse body. These portions of each of the fuse elements 11 are disposed. Each of the cavities 34 connects with a circular groove 35 in the top shoulder 32 and in the fuse body. This circular groove 30 is for 15 the purpose of accommodating the contact finger 36 adapted to selectively make contact with each of the upper ends of the fuse elements 11. More particularly the contact finger 36 is in electrical connection with the contact ring 37 secured upon 20 the shoulder 32 of the core of the fuse. This contact ring 37 not only extends across the groove 35, but also extends over the upper end of a connection 38 which is in electrical connection with the contact shell 14. Thus in all positions of 25 rotation of the core there will be an electrical connection between the contact shell 14 and the ring 37. From the ring 37 the current may continue to the contact finger 36, which in practice preferably should be integral with the ring 37 30 as clearly shown in Fig. 5, and hence to one of the fuse elements 11 depending upon which of the cavities 34 the contact finger 36 engages in.

Inspecting Fig. 6 it should be noticed that the core is in contact with the inner face of the fuse body and so closes possible passage of flames and fumes between the grooves in which the fuse elements 11 are displaced. Furthermore it should be borne in mind that the fire resistant material 26 is stationarily secured within the cap 23 which 35 in turn is also stationary relative to the fuse body. It is necessary that the fire resistant material 26 and the cap 23 be stationary so that the V-shaped opening 28 properly aligns with the openings 27 to blacken the fire resistant material 40 26 and indicate which of the fuse elements are blown. The electric circuit may be traced from the central contact 12 through each of the fuse elements 11. The circuit then continues from one of the fuse elements to the contact finger 45 36, the ring 37, the connection element 38 to the contact shell 14. When the particular fuse element 11 blows the flame and fumes fill the fume chamber 17 and then pass through the openings 20 to the peripheral groove fume chamber 19 50 and from there through the passages 25 to the atmosphere. Particular attention is called in the fact that as the flame and fumes fill the fume chamber 17 they cause the air to back up through the unrestricted passages 20 into the second fume chamber 19 and the atmosphere under the 55 restrictions of the passages and thus create a back pressure which serve to extinguish the flame. Then the fumes may escape through the restricted passages 25. The construction of the 60 double fume chamber with the restrictions to create the back pressure is a very important part of the invention since it prevents the flame from reaching the exterior of the fuse plug which would be a fire hazard. The sum total of the 65 passages 25 should be materially smaller, in other words, restricted, relative to the sum total of the passages 20 for helping and creating the back pressure.

In Fig. 7 a modification of the invention has 70 been disclosed in which a key is necessary to

rotate the core for resetting the fuse from one condition. In detail, a plurality of tumblers 40 are arranged in openings extending from the core section 15 into a protuberance 41 connected with the cap 23. A key 42 is adapted to engage with 5 in a key opening in the top of the core and move the tumblers 40 into positions in which the core is free to rotate. The drawing shows only one group of tumblers for locking the core in one position only corresponding with one fuse. 10 Further details of the lock construction will not be given here since anyone skilled in the art would understand its construction from the brief explanation. Thus unauthorized persons cannot turn the core for resetting the multiple fuse. 15

While I have illustrated and described my invention with some degree of particularity, I realize that in practice various alterations therein may be made. I therefore reserve the right and privilege of changing the form of the details of 20 construction or otherwise altering the arrangement of the correlated parts without departing from the spirit or the scope of the appended claims.

Having thus described my invention, what I 25 claim as new, and desire to secure by United States Letters Patent is:—

1. In a multiple fuse, a body with a plurality of fuse elements, a core rotative within said body and formed with an interior fume chamber having an entrance port selectively engageable over 30 said fuse elements, said core having a peripheral groove fume chamber connecting with restricted discharge passages to the atmosphere and connected with unrestricted openings to said interior 35 fume chamber, and a cap engaging over said peripheral groove fume chamber and a portion of said body.

2. In a multiple fuse, a body with a plurality of 40 fuse elements, a core rotative within said body and formed with an interior fume chamber having an entrance port selectively engageable over said fuse elements, and means for visually indicating the blowing of each fuse element.

3. In a multiple fuse, a body with a plurality of 45 fuse elements, a core rotative within said body and formed with an interior fume chamber having an entrance port selectively engageable over said fuse elements, said core having a peripheral groove fume chamber connected with openings 50 to said interior fume chamber, a cap engaging over said peripheral groove fume chamber and a portion of said body and adapted to allow the gradual escape of fumes to the atmosphere, and means for visually indicating the blowing of each 55 fuse element, comprising fire resistant material within said cap and stationarily connected therewith and transparent or translucent in nature and located beneath apertures formed in said cap corresponding selectively with said fuse elements, and said core being formed with an opening connecting said peripheral fume groove chamber with an area of said fire resistant material located beneath one of the openings in said cap. 60

4. In a multiple fuse, a body with a plurality of 65 fuse elements, a core rotative within said body and formed with an interior fume chamber having an entrance port selectively engageable over portions of said fuse elements, and said body 70 and core having interengaging shoulders, said fuse elements following the contour between said core and body and being located in grooves in one of said members, each fuse element having a reduced portion adapted to direct at the proper 75

time the flames and fumes into said entrance port, said core being composed of an upper and a lower section connected for unitary rotation, with the provision of a finger from one of the 5 sections engaging in an opening in the other section, said latter mentioned opening comprising said entrance port.

5. In a multiple fuse, a body with a plurality of fuse elements, a core rotative within said body 10 and formed with an interior fume chamber having an entrance port selectively engageable over portions of said fuse elements, and said body and core having interengaging shoulders, said fuse elements following the contour between said core 15 and body and being located in grooves in one of said members, each fuse element having a reduced portion adapted to direct at the proper time flames and fumes into said entrance port, the upper ends of each of the fuse elements being 20 extended horizontally beneath one of the shoulders between said body and core and within cavities in said shoulder, and a contact spring upon the core selectively engageable within said cavities to make electrical contact with said fuse 25 element.

6. In a multiple fuse, a body with a plurality of fuse elements, a core rotative within said body and formed with an interior fume chamber having an entrance port selectively engageable over 30 portions of said fuse elements, and said body and core having interengaging shoulders, said fuse elements following the contour between said core and body and being located in grooves in one of said members, each fuse element having a reduced portion adapted to direct at the proper time 35 flames and fumes into said entrance port, the upper ends of each of the fuse elements being extended horizontally beneath one of the shoulders between said body and core and within cavities in said shoulder, and a contact spring upon the core selectively engageable within said cavities to make electrical contact with said fuse element, said horizontal contact finger being connected with a contact ring secured upon the latter mentioned shoulder of said core and in electrical 40 contact with a member extended through the fuse body and connected with the contact shell of said fuse.

7. In a multiple fuse, a body with a plurality of fuse elements, a core rotative within said body and formed with an interior fume chamber having an entrance port selectively engageable over portions of said fuse elements, and said body and core having interengaging shoulders, said 50 fuse elements following the contour between said core and body and being located in grooves in one of said members, each fuse element having a reduced portion adapted to direct at the proper time flames and fumes into said entrance port, the upper ends of each of the fuse elements 55 extended horizontally beneath one of the shoulders between said body and core and within cavities in said shoulder, and a contact spring upon the core selectively engageable within said cavities to make electrical contact with said fuse element, said horizontal contact finger being 60 connected with a contact ring secured upon the latter mentioned shoulder of said core and in electrical contact with a member extended through the fuse body and connected with the contact shell of said fuse.

nected with a contact ring secured upon the latter mentioned shoulder of said core and in electrical contact with a member extended through the fuse body and connected with the contact shell of said fuse, said horizontal contact finger 5 being integral with said contact ring.

8. In a multiple fuse, a fuse body, a core rotative therein for changing the connection through the various fuse elements of said multiple fuse, and a lock interposed between said core and a 10 stationary part of said fuse body for holding said core against rotation.

9. In a multiple fuse, a fuse body, a core rotative therein for changing the connection through the various fuse elements of said multiple fuse, 15 and a lock interposed between said core and a stationary part of said fuse numerally for holding said core against rotation, said lock comprising a plurality of spring urged tumblers between said core and said stationary element, and a key 20 opening adapted to receive a key capable of moving said tumblers into their open positions.

10. In an article of the class described having a plurality of fuse links, an interior fume chamber selectively engageable over the portion of 25 each of the fuse links which blows to open the circuit, and a second fume chamber joined with said interior fume chamber with unrestricted passages and itself having fume escape passages restricted relative to said unrestricted passages. 30

11. In a multiple fuse, an interior fume chamber selectively engageable over the portion of each fuse link which blows to open the circuit, and a second fume chamber joined with unrestricted passages with said interior fume chamber, said second fume chamber having fume escape restricted passages. 35

12. In a multiple fuse, an interior fume chamber with a small entrance port selectively engageable over the portion of each fuse link which 40 blows to open the circuit, a second fume chamber, joined with said interior fume chamber with unrestricted passages and itself having fume escape passages restricted relative to said unrestricted passages. 45

13. In a multiple fuse, a rotative core formed with an interior fume chamber selectively engageable over the fuse elements, and said core having a second fume chamber joined with unrestricted passages with said interior fume chamber, said second fume chamber having fume escape passages restricted with relation to said unrestricted passages. 50

14. In a multiple fuse, a rotative core formed with an interior fume chamber selectively engageable over the fuse elements, and said core having a second fume chamber joined with unrestricted passages with said interior fume chamber, said second fume chamber having fume escape passages restricted with relation to said unrestricted passages, said interior fume chamber being longitudinal within the core, and said second fume chamber being peripheral around said core. 55
